UNITED STATES PATENT OFFICE.

CLYDE DUNCAN, OF DETROIT, MICHIGAN.

COMBINATION FOUNTAIN PEN.

Application filed May 23, 1925. Serial No. 32,427.

To all whom it may concern:

Be it known that I, CLYDE DUNCAN, a citizen of the United States, residing at Detroit, in the county of Wayne and State 5 of Michigan, have invented a new and useful Improvement in a Combination Fountain Pen, of which the following is a specification.

My invention relates to a new and useful 10 improvement in a combination fountain pen and has for its object the combination with a fountain pen of a printing arrangement whereby the fountain pen may be used for printing a single letter at a time.

Another object of the invention is the 15 provision of a fountain pen having an auxiliary barrel in which is positioned an endless belt carrying the letters of the alphabet and so arranged and constructed that the belt 20 may be moved to present, at an open space in the auxiliary barrel, a single letter at a time for printing purposes.

Another object of the invention is the 25 provision of a fountain pen having an auxiliary barrel, in which is positioned an endless belt carrying the letters of the alphabet, movable to operative position at will, and adapted for engaging an inking pad in 30 movement, the ink being supplied to the inking pad from the reservoir of the pen.

Other objects will appear hereinafter.

The invention consists in the combination and arrangement of parts hereinafter described and claimed.

The invention will be best understood 35 from a reference to the accompanying drawings, which form a part of this specification and in which,

Fig. 1 is a side elevational view of the 40 invention, showing the cap slightly removed,

Fig. 2 is a fragmentary sectional view, taken on substantially line 2-2 of Fig. 1,

Fig. 3 is a longitudinal vertical central 45 sectional view of the invention, showing a part in side elevation,

Fig. 4 is a fragmentary sectional view taken on substantially line 4-4 of Fig. 2,

Fig. 5 is a sectional view taken on substantially line 5-5 of Fig. 3.

As shown in the drawings, the pen is provided with a neck 9, in which is mounted in the conventional manner the pen point 10. The base of the neck 9, which is enlarged, is provided with a passageway 11, 50 adapted for leading ink from the reservoir 12 to the pen 10. The base 13 of the reser-

voir 12 is projected into a recess 14 formed in the enlarged portion of the neck 9. Flanges 15 and 16 are adapted for embracing the auxiliary barrel or shell 17, along 60 one edge, the side embraced being open throughout the major portion of its length, and provided adjacent its rear with a transparent closure 18. Mounted in the auxiliary barrel 17, adjacent its rear end, preferably 65 by a pressfit, is an ink well 19 having the chamber 20 formed therein, adapted for the reception of ink from the reservoir 12, through the opening 24.

Formed in the base of the inkwell 19 is 70 an opening 22, which permits the flow of ink from the chamber 20 onto the inking pad 23.

Mounted on a shaft 25, which is journaled in the side walls of the auxiliary barrel 17 is a roller 26. A gear 27 is mounted in 75 the auxiliary barrel 17 at the end opposite to the end at which the roller 26 is mounted, said gear 27 being rotatably mounted on the shaft 28, which is mounted in the side walls of the auxiliary barrel 17. The gear 27 80 is adapted to mesh with a gear 30, which is mounted upon a shaft, supported by the side walls of the auxiliary barrel 17. As clearly seen in Fig. 4, the auxiliary barrel 17 is cutaway as at 31. Mounted over the gear 30 and the roller 26 is an endless belt 85 32 carrying a plurality of blocks 33, which are slightly spaced apart.

Each of the blocks 33 bears on its face one of the letters of the alphabet, so that 90 these blocks may be termed "printing blocks", as they serve to afford a means of printing the letters of the alphabet singly.

As shown in Fig. 4, the blocks 33 are adapted to project through the opening 31, 95 so that they are projecting outwardly sufficiently to engage a paper or other surface, upon which printing may be desired.

Mounted exteriorly of the shell 17 is a 100 disc 29, which is fixedly mounted upon the shaft 28. The construction is such that the user, by turning the disc 29, will cause the traveling of the belt 32, so as to bring the several letter bearing blocks into registration 105 with the opening 31. As the belt travels along, the several blocks are brought into contact with the inking pad 23. The operator, by looking through the transparent closure 18, may determine when the letters desired 110 are approaching the opening 31. Slidably mounted between the inkwell 19 and the base 13 of the reservoir 12 is a

closure 34 having its outwardly projecting end 34' turned upwardly to provide a gripping portion. By sliding the closure so as to cover the opening 24, the flow of ink from the reservoir 12 to the inkwell 19 will be stopped. A suitable cap 36 is adapted for covering the butt end of the fountain pen, said cap 36 being provided with an elongated slot 35, adapted to accommodate the shaft 10 28.

The invention is particularly adapted for use in marking letters in small spaces, such as is required in working out crossword puzzles. The structure illustrated is believed to be a simple one for the purpose and one which is durable.

While I have illustrated and described the preferred form of structure, I do not wish to limit myself to the precise form of structure shown but desire to avail myself of such variations and modifications as come within the scope of the appended claims.

Having thus described my invention, what I claim as new and desire to secure by Letters Patent is:

1. A combination fountain pen of the class described, comprising a neck having a passage formed therein; an ink reservoir mounted on said neck and communicating with said passage; a housing mounted on said neck; a roller mounted in said housing; an endless belt mounted on said roller and carrying on its outer surface printing symbols; gears mounted in said housing and adapted for effecting the movement of said belt, said gears being positioned adjacent an opening formed in said housing for projecting said printing symbols exteriorly of said housing individually; and an inking pad adapted for engaging said belt upon movement of said belt, an opening communicating said reservoir with said housing, said pad being inked from said reservoir through said opening.

45 2. A combination fountain pen of the class described, comprising a neck having a passage formed therein; an ink reservoir mounted on said neck and communicating

with said passage; a housing mounted on said neck, an opening being provided for establishing communication between said housing and said reservoir; a slidable member for opening and closing said opening; a well positioned in said housing beneath said opening; an absorbent pad mounted on the undersurface of said well, the base of said well having an opening formed therein; a roller mounted in said housing; an endless belt mounted in said housing, said belt being extended around said roller; a gear mechanism mounted in said housing adapted for effecting a traveling of said belt, said belt having printing characters formed on its outer surface, said printing characters being adapted for engaging said absorbent pad upon travel of said belt.

3. A combination fountain pen of the class described, comprising a neck having a passage formed therein; an ink reservoir mounted on said neck and communicating with said passage; a housing mounted on said neck, an opening being provided for establishing communication between said housing and said reservoir; a slidable member for opening and closing said opening; a well positioned in said housing beneath said opening; an absorbent pad mounted on the undersurface of said well, the base of said well having an opening formed therein; a roller mounted in said housing; an endless belt mounted in said housing, said belt being extended around said roller; a gear mechanism mounted in said housing adapted for effecting a traveling of said belt, said belt having printing characters formed on its outer surface, said printing characters being adapted for engaging said absorbent pad upon travel of said belt.

In testimony whereof, I have signed the foregoing specification.

CLYDE DUNCAN.
